UNITED STATES PATENT OFFICE.

JOHN D. ZIELEY, OF NEW YORK, AND FERDINAND A. RUDOLF, OF JAMAICA, NEW YORK.

DISTILLATION OF CARBONACEOUS MATERIAL.

Application filed October 15, 1920. Serial No. 417,083.

Our invention relates to the production of hydrocarbons of low molecular weight from hydrocarbons of higher molecular weight and particularly to that treatment which is known to those skilled in the art as cracking or destructive distillation. The object of our invention is to obtain from substances rich in such material, hydrocarbons such as gasoline, benzine, naphtha, and the like, by subjecting the rich hydrocarbonaceous material to the extremely high temperature which is necessary to bring about a breaking up of the molecules and a redistribution of the same to form the desired compounds.

In the accompanying drawing, we have illustrated in vertical section, parts being broken away, an illustrative form of apparatus by which the method of our invention may be practiced.

In said drawing, 1 indicates the chamber of a vertical type of gas retort producer into which hydrocarbonaceous material such as coal may be introduced through a suitable hopper such as 3. 2 indicates the ash pit which is preferably gas-tight except for the injector pipes hereinafter referred to. 4 indicates the vapor outlet running to condensers (not shown). 5 indicates a suitable blow-off and exhaust for blow-up gases. 6—6' are the air feeds, and 7—7' the steam injectors. 8 indicates the salt injectors where required, and 9 the heavy condensate return. 10 is a check trap regulating the direction of flow.

Any grade of coal may be fed into the retorts through hoppers such as 3, one high in hydrocarbon being preferred. Before charging however, the coal is saturated with a solution of salt preferably sodium chloride of a predetermined strength. After igniting the coal which may be done by any suitable means, the blow-up chamber upon the outlet 5 is closed and air is let into the ash pit in regulated quantity to support combustion sufficiently to maintain a temperature of say 2500° F. in the lower part of the chamber 1. Steam is now turned into the pit through the injectors 7 and this rises through the heated coal and salt. Complicated reactions set in between the hydrocarbons and carbon of the coal, the hydrogen and oxygen of the steam, and the sodium and chlorine of the salt. Due to the extremely high temperature in the chamber 1, the sodium chloride and steam are decomposed, and enter into complex reactions with the hydrocarbons of the coal so that a complete rearrangement of the molecules takes place. The action of the sodium chloride is believed to be catalytic and it enters temporarily into the reactions but forms no substantial part of the hydrocarbon vapors which finally pass off through the pipe 4 into the condensers. The salt remains substantially in the combustion chamber and may be used again for successive distillations.

If the supply of sodium chloride becomes exhausted or if it loses its catalytic power so that the speed of the reaction is impeded, a fresh supply may be introduced from time to time through the pipes 8 leading from tower 8'.

The products which pass to the condenser through the pipe 4 are hydrocarbons which are liquid at ordinary temperatures and pressures, such as gasoline, benzine, naphtha, and the like. The heavy condensate passes by pipe 9 into the trap 10, the flow being regulated by the trap 10, and also back through the pipe 4 into the combustion chambers in the opposite direction from the outgoing vapors.

A powder coal burner may of course be used and powdered coal may be injected with steam and salt solution relatively regulated as may be found necessary, instead of employing lumps of coal as previously set forth, and in fact various modifications may be made in the several steps of the process and in the details of the apparatus illustrated without departing from the spirit of the invention as claimed.

Having now fully described our invention, what we claim as new and desire to secure by Letters Patent is:

1. Process for producing liquid hydrocarbons from coal or other solid hydrocarbonaceous fuel which comprises continuously distilling such material in the presence of sodium chloride, condensing the products of distillation and introducing from time to time fresh quantities of sodium chloride as desired to expedite the reaction.
2. A process for the production of liquid hydrocarbon, comprising impregnating a solid hydrocarbonaceous fuel with a solution of sodium chloride, introducing said hydrocarbonaceous fuel into a chamber, igniting the fuel, and maintaining combustion in the chamber at a temperature of approximately 100° F.

2500 degrees F. by means of air and steam introduced from the bottom of the chamber.

3. In a process for the production of liquid hydrocarbons, comprising impregnating a solid hydrocarbonaceous fuel with a solution of sodium chloride, introducing said hydrocarbonaceous fuel into a chamber, igniting the fuel, and maintaining combustion in the chamber by means of air and steam introduced from the bottom of the chamber, introducing from time to time fresh quantities of sodium chloride as desired to expedite the reaction.

4. A process for the production of liquid hydrocarbons, comprising impregnating coal with a solution of sodium chloride, introducing said coal into a chamber, igniting the coal, maintaining combustion in the chamber at a temperature of approximately 2500° F.

by means of air introduced from the bottom 26 of the chamber, and condensing the vapors evolved from said coal.

5. In a process for the production of liquid hydrocarbons, comprising impregnating coal with a solution of sodium chloride, introducing said coal into a chamber, igniting the coal, and maintaining combustion in the chamber by means of air introduced from the bottom of the chamber, introducing from time to time fresh quantities of sodium chloride 25 30 as desired to expedite the reaction, and condensing the vapors evolved from said coal.

In testimony whereof we hereunto affix our signatures.

JOHN D. ZIELEY.
FERDINAND A. RUDOLF.
